UNITED STATES PATENT OFFICE.

CHARLES DAVID BON-SALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed November 19, 1924. Serial No. 750,839.

To all whom it may concern:

Be it known that I, CHARLES DAVID BON-SALL, a citizen of the United States, and a resident of the city of Pittsburgh, county 5 of Allegheny, and State of Pennsylvania, have invented a new and useful Improvement in Car Roofs, of which the following is a specification.

This invention relates to car roofs of the 10 all-steel type wherein the roof sheets extend from side plate to side plate and are connected along their side margins by up-standing seams that are covered by weather-proofing caps which function as exterior 15 carlines or frame members to brace and stiffen the car body.

One of the principal objects of the present invention is to produce a roof of the above type which will be stiffer and stronger 20 than previous roofs of the same weight of metal. Other objects are simplicity, durability, and cheapness of construction.

The invention consists principally in a roof of the above type wherein the sheets 25 are rigidly secured together and to the side plates and have a snug fit in the carlines, whereby said sheets serve as direct frame members in combination with the carlines to brace and stiffen the car body. The invention 30 also consists in the parts and in the combinations and arrangements of parts hereinafter described and claimed.

In the accompanying drawing, which forms part of this specification and wherein 35 like symbols refer to like parts wherever they occur,

Fig. 1 is a plan view of a portion of a car roof embodying my invention;

Fig. 2 is an enlarged transverse section 40 through one-half of the roof on the line 2-2 in Fig. 1;

Fig. 3 is an enlarged vertical cross-section 45 through one of the roof seams, the section being taken through one of the supporting brackets for the running boards on the line 3-3 in Fig. 2;

Fig. 4 is a similar section taken in the 50 region of one of the bolts that secure the lapped seam flanges together on the line 4-4 in Fig. 2; and

Fig. 5 is a similar cross-section at the 55 eaves of the car on the line 5-5 in Fig. 2.

The present roof comprises transversely 60 arranged load sustaining metal roof sheets 6, which extend from eaves to eaves of the

car. The eaves ends of the roof sheets are supported on and positively secured to the outwardly extending flanges of angle-bar side plates 7 by rows of rivets 8 and are preferably provided at their eaves ends with 60 depending drip flanges 9 that overhang the outer edges of the side plates. The roof sheets, which are pressed from rectangular blanks of sheet metal, slope downwardly on opposite sides of the ridge to form a pitch 65 or arcuate roof and are provided along their adjacent side margins with raised hollow ribs or seam flanges 10 having flat tops and sides.

The hollow rib of one sheet overlaps the 70 hollow rib of the next adjacent sheet, thus forming a hollow seam A between the body portions of the sheets. Each of these ribs or seam flanges 10 comprises an upstanding web portion extending upwardly from the 75 body of the sheet and having at the top thereof a lateral top flange whose outer edge is provided with a depending lip or flange. The ribs are preferably of uniform width and depth from the ridge to points 80 adjacent to the eaves where they are curved downwardly and merge into the plane of the body of the sheets adjacent to the inner faces of the side plates, whereby said sheets have wide flat eaves end portions adapted 85 to bear flatwise on the side plates. The surplus metal gained by stopping the ribs short of the eaves is utilized in widening the flat eaves portions of the roof sheets, thereby increasing the extent of the sheet 90 lap at the eaves and providing space for additional rivets for securing the lapping portions of the sheets together and to the side plates. By this arrangement, the sheets act after the manner of braces or 95 gussets to resist lateral stresses which tend to distort the car frame. The overlapped ribs or seam flanges are rigidly secured together, preferably at points adjacent to the ridge and eaves, by bolts 11 that extend through registering holes in the tops of the ribs or seam flanges and are threaded at 100 their lower ends to receive nuts.

The hollow upstanding roof seams are straddled by inverted channel-shaped stiffening members or caps 12 provided with lateral base flanges 13 that rest on the body portions of the sheets and opposite sides of the seams. The stiffening members or caps, which constitute outside carlines, 110

5 closely embrace the upstanding roof seams and extend from eaves to eaves of the car where they are provided with depending eaves flanges 14 that overlap the depending eaves flanges 9 of the adjacent roof sheets. 10 The channel-shaped rib portions of the outside carlines are curved downwardly at the eaves and merge into the plane of the base flanges 13 at points where they are turned down to form the depending end flanges 14. 15 The surplus metal resulting from the down-turned eaves end portions of the carlines is utilized in widening out the eaves end portions of the base flanges which are secured to the side plates by the rivets 8 which 20 secure the flat overlapped eaves portions of adjacent sheets to the side plates. The roof seams have a snug fit in the carlines, but are of considerably less depth than the carlines, thereby providing spaces between the top of said seams and the top of the said carline sufficient to accommodate the bolts 25 that secure the lapped seam flanges together.

25 Running boards 15 extend longitudinally of the car at the ridge and are secured to the running board saddles 16 located above the carlines. The running board saddles 16 extend longitudinally of the carlines at the 30 ridge and are secured thereto by angle-shaped brackets 17. One flange of a bracket 17 projects upwardly and is rigidly secured to one side of the running board saddle by a horizontal bolt 18; and the other flange of said bracket rests on the top of the carline and is preferably secured thereto by means of rivets.

40 With the arrangement described, the roof sheets are positively secured to each other and to the side plates and the carlines closely embrace the roof seams and thus act after the manner of sheaths to stiffen said seams, whereby the sheets and carlines cooperate in strengthening the roof and stiffening the roof frame against stresses tending to distort said frame and shear the securing rivets. It is noted that this increased strength in the seams or joints enables a roof to be produced that will be 45 stiffer and stronger than previous roofs of the same weight of metal. It is also noted that the outside carlines cover the bolts that secure together the seam flanges of adjacent sheets and thereby prevent leakage 50 around the bolts.

55 The hereinbefore described arrangement is applicable to roofs having side plates and seams of various sections; therefore, I do not wish to be limited to the exact side plate and seam constructions shown in the drawing.

60 What I claim is:

65 1. A car roof comprising a plurality of load sustaining roof sheets extending from side plate to side plate and rigidly connect-

ed thereto and to each other, said sheets having hollow upstanding ribs formed therein extending transversely of the car, and outside carlines extending from side plate to side plate and rigidly secured thereto, said carlines covering said hollow ribs and snugly fitting the sides thereof.

2. A car roof comprising a plurality of load sustaining roof sheets extending from side plate to side plate and rigidly connected thereto and to each other, said roof sheets having hollow upstanding ribs formed in their adjacent side marginal portions that are lapped and rigidly secured together to form hollow seams extending transversely of the car, and outside carlines of substantially inverted channel-shaped section extending from side plate to side plate and rigidly secured thereto, said carlines covering said ribs and closely embracing the sides thereof.

3. A car roof comprising a plurality of roof sheets extending from side plate to side plate and rigidly secured thereto, said roof sheets having their adjacent side marginal portions shaped and rigidly secured together to form hollow upstanding seams, and outside carlines extending from side plate to side plate and rigidly secured thereto, said carlines straddling said hollow seams with their side walls in direct contact with the side walls of the seams.

4. A car roof comprising a plurality of load sustaining roof sheets extending from side plate to side plate and rigidly connected thereto, their adjacent side marginal portions shaped and rigidly secured together to form hollow upstanding seams that extend transversely of the car, and outside carlines covering said seams and rigidly secured to said side plates, said carlines closely embracing the sides of said hollow seams and being spaced from the tops thereof.

5. A car roof comprising a plurality of load sustaining roof sheets extending from side plate to side plate and rigidly connected thereto, their adjacent side marginal portions shaped and rigidly secured together to form hollow upstanding seams that extend transversely of the car, outside carlines covering said hollow seams and rigidly secured to said side plates, said carlines closely embracing the sides of said seams and being spaced from the tops thereof, and running board saddles supported by and secured to said carlines independently of said roof seams.

6. A car roof comprising a plurality of roof sheets extending from side plate to side plate and rigidly secured thereto, said roof sheets having upwardly offset side marginal portions that are lapped to form hollow upstanding seams, and outside carlines extending from side plate to side plate and rigidly secured thereto, said carlines straddling

said hollow seams with their side walls in direct contact with the side walls of the seams.

7. A car roof comprising a plurality of 5 roof sheets extending from side plate to side plate and rigidly secured thereto, said roof sheets having upwardly offset side marginal portions that are lapped and rigidly secured together to form hollow upstanding 10 seams of substantially inverted channel-

shaped section, and outside carlines of substantially channel-shaped section extending from side plate to side plate and rigidly secured thereto, said carlines straddling said hollow seams with their side walls in direct contact with the side walls of the 15 seams.

Signed at New Kensington, Pa., this 14th day of Nov., 1924.

CHARLES DAVID BONSALL.
